LIFTING JACK

Alexis Jackson, Westport, Conn., assignor to
Vadim S. Makaroff, New York, N. Y.

Application July 31, 1943, Serial No. 496,883

6 Claims. (Cl. 254—8)

1

My invention relates to lifting jacks and has particular reference to portable jacks for lifting various objects, and more particularly to jacks operated by a fluid under pressure.

My invention has for its object to provide a lifting jack which can be used for lifting such objects as automotive vehicles from relatively low elevation, as, for instance, when a tire on the vehicle wheel is flat and there is very little room under the axle to place a lifting jack therein.

In my United States Patent No. 2,230,250, issued February 4, 1941, I disclosed a lifting jack of a similar construction, which can be placed under a low positioned axle of an automotive vehicle. I have found, however, that automotive vehicles often have projecting parts, such as bumpers, etc., extending far to the rear of the axle so that the jack must have sufficient low clearance practically throughout its full length. It was found that certain parts of the jack disclosed in the foregoing patent interfere with the insertion of the jack under long low-hung bodies.

In my present invention I have modified the construction by moving the operating cylinder to the rear of the lifting arms, and eliminating other connecting parts which may interfere with the insertion of the jack in its place.

My invention is more fully described in the accompanying specification and drawing, in which:

Fig. 1 is an elevational view of my jack in an inoperative position with the lifting arm lowered;

Fig. 2 is a similar view of the jack in an operative position with the lifting arm raised;

Fig. 3 is a sectional detail view of the operating cylinder; and

Fig. 4 is a top plan view of the jack.

My lifting jack consists of a frame formed of a pair of arms 1 connected at the front by an axle 2 with supporting wheels 3. The rear ends of the arms 1 are pivotally mounted on trunnions 4 extending from a reinforcing ring 5 on the open lower end of a cylinder 6, the upper end of the cylinder being closed.

The frame arms 1 are rotatively mounted on a shaft 7 which also mounts a lifting member consisting of a pair of lifting arms 8 with hooks 9 at the front ends for engaging an object to be raised such as an axle of an automotive vehicle (not shown). The rear ends of the lifting arms are pivotally mounted on a rod 10 passing through the lower end of a tubular piston 11 sliding in the cylinder 6. The ends of the rod 10 extend beyond the ends of the frame arms 1 and mount

2

supporting wheels 12. The lifting arms are connected together as by a rod or tube 13.

Piston 11 is provided with a sealing disc 14, Fig. 3, made of leather or other suitable material, tightly fitted in the cylinder and fastened to the closed top of the piston as by a bolt 15.

A valve 16 is provided on top of the cylinder for admitting compressed air into the cylinder, the valve being preferably of a type used with inner tubes of automobile tires so that the same air hose which is used for pumping tires can be used to operate by lifting jack. The valve is of a one-way type, i. e., for admitting the air but not for discharging the same. For the latter purpose a pipe 17 is provided extending from the closed top of the piston 11 inside the piston and connected with an outer nipple 18 to which a flexible hose 19 is attached. The hose is in turn connected with a pipe 20 supported inside a hollow rod 21 pivotally attached to a lug 22 extending from the lower end of the piston, the upper end of the rod having a handle 23 in the form of a cross-bar. A valve 24 is provided at the top of the pipe 20 for releasing the air from the piston when it is desired to lower the lifting arms. The handle can be used for moving the lifting jack around and for placing it in an operative position under an automobile.

For locking the lifting arms in a raised position as shown in Fig. 2, the piston 11 has holes 25 for a locking rod 26 which, when inserted in a corresponding hole, prevent the cylinder 6 from sliding down over the piston. The rod, when not in use, is held in a socket 27 at the side of the cylinder 6 as shown in Fig. 1.

Distance from the rear ends of the lifting arms to the common shaft 7 is considerably smaller than the distance from the shaft 7 to the front ends of the lifting arms so that the arms can be raised to a considerable height with a relatively small travel of the piston.

My lifting jack has an important advantage in that both sets of arms, frame and lifting, lie very low as is shown in Fig. 1 so that the jack can be moved under a very low vehicle without interference with long overhanging parts such as bumpers, trunks, spare tires, etc.

It will be noted, particularly from Fig. 1, that the motor is inclined upwardly and away from the front end of the jack when in collapsed condition, thus further increasing bumper clearance. It will furthermore be noted that the horizontal pivot shaft 7 connects the frame and lifting members in such manner as to cause these members to execute a movement not unlike a common

scissors and that this pivot shaft divides these members into relatively long front levers and relatively short rear levers; that the stroke of the motor is only slightly greater than the length of the rear levers; that the lifting member occupies a position nearer the vertical and the frame occupies a position near the horizontal when the jack is in its highest raised position. It will also be seen that the distance between wheels 3 and 12, defining the wheel or supporting base contracts comparatively little as the jack is raised. It will be seen from a comparison of Figs. 1 and 2 that because of this dissymmetry of construction the stability of the jack changes from the position of relatively small stability shown in Fig. 1, to the position of relatively great stability shown in Fig. 2, when the jack is raised from its collapsed position to its highest position.

It is understood that the cylinder may be of any suitable type for operation by compressed air or other elastic fluid, also to be operated by an incompressible fluid such as oil, or by combination of the two fluids.

It is understood that my lifting jack may be further modified without departing from the spirit of the invention, as set forth in the appended claims.

I claim as my invention:

1. A lifting jack comprising a frame; means to movably support the front end of the frame on the ground, the rear end of the frame being adapted to be raised from the ground; a lifting member pivotally connected to the frame by a horizontal pivoting member, the front end of the lifting member being adapted to engage an object to be lifted; means to movably support the rear end of the lifting member on the ground; a motor consisting of two telescopic members, one telescopic member being pivotally connected to the rear end of the frame, the other telescopic member being pivotally connected to the rear end of the lifting member, one telescopic member being in the form of a cylinder closed at the outer and open at the inner end, the other telescopic member being in the form of a piston slidably fitted in the cylinder; a one-way valve on the cylinder for admitting a fluid under pressure in the cylinder thereby causing the lifting member to be raised; a handle extending from the rear end of the motor; a pipe extending from the handle into the cylinder; and a manually operable valve on the pipe for releasing the fluid from the cylinder thereby allowing the lifting member to be lowered.

2. In a lifting jack for lifting one end of an automotive vehicle high off a supporting surface, said jack comprising a frame having a pair of spaced arms, a cross-member secured to said arms near their front ends, wheels journaled on said frame to movably support the front end of the frame on the supporting surface, the rear end of the frame being adapted to be raised from the supporting surface, a lifting member comprising spaced arms positioned within said frame arms, a horizontal pivoting member connecting said frame arms and lifting arms, said pivoting member dividing said frame and lifting member into relatively long front levers and relatively short rear levers, the front end of the lifting member being adapted to engage one end of said automotive vehicle for lifting the same, wheels on the rear ends of said lifting arms for movably supporting the rear end of said lifting member on the supporting surface, a motor comprising a piston and a cylinder, the lower end of said piston

being pivoted to the rear end of said lifting arms, said cylinder being disposed above said piston, said cylinder having its upper end closed and its lower end located between the rear ends of said frame arms and pivoted thereto, means for supplying said motor with fluid for causing the piston and cylinder to move apart thereby raising the front end of said lifting member, and causing it to move from a position of relatively low stability to a position of relatively great stability.

3. In a scissors type, high lift jack, a frame; means to movably support the front end of the frame on a supporting surface, the rear end of said frame being adapted to be raised from said supporting surface, a lifting member pivotally connected to the frame by a pivoting member which divides said frame and lifting member into relatively short rear levers and relatively long front levers, the front end of the lifting member being adapted to engage the load to be lifted, means for movably supporting the rear end of said lifting member on said supporting surface, a motor comprising expandable members pivotally connected to the rear ends of said frame and lifting member for moving said rear ends apart, said motor members being expandable from a position representing a substantially collapsed condition of the jack to a distance at least equal to the length of said shorter levers and representing a condition where said lifting member is nearer the vertical than horizontal while said frame member is nearer horizontal than vertical.

4. In a scissors type, high lift jack, a frame, a lifting member, pivot means connecting said frame and lifting member, said pivot means dividing said frame and lifting member into relatively long front levers and relatively short rear levers, devices for movably supporting the rear end of said lifting member and the front end of said frame on a supporting surface, the front end of the lifting member having a load-elevating portion located adjacent the front end of the frame when the jack is collapsed so that the jack has relatively low stability when in such collapsed condition, a relatively short stroke motor comprising movable members pivotally connected to the rear ends of said lifting member and frame for elevating the latter, whereby the stroke of said motor raises said load-elevating portion proportionally more than the stroke of said motor and substantially increases the stability of said jack from its condition of relatively low stability to a condition of relatively great stability.

5. In a scissors type, high lift jack, a frame, a lifting member, pivot means connecting said frame and lifting member, said pivot means dividing said frame and lifting member into relatively long front levers and relatively short rear levers, devices for movably supporting the rear end of said lifting member and the front end of said frame on a supporting surface, the front end of the lifting member having a load-elevating portion located adjacent the front end of the frame when the jack is collapsed so that the jack has relatively small stability when in low position, a relatively short stroke motor operating between the rear ends of said lifting member and frame for elevating the latter, the dissymmetrical arrangement of said pivot means causing the elevating movement of said motor to raise said load-elevating portion proportionally more than the stroke of said motor, and said frame to retain a position generally nearer the horizontal than vertical, and said load-elevating portion to swing further within the supporting base defined by said

supporting devices to give the jack relatively great stability when raised.

6. In a scissors type jack for lifting an automobile, a frame, a lifting member, pivot devices connecting said frame and lifting member, said pivot devices dividing said frame and lifting member into relatively long front levers and relatively short rear levers, the front end of the lifting member having a load elevating portion adapted to engage the automobile, wheeling devices for movably supporting the rear end of said lifting member and the front end of said frame on a supporting surface, an upright motor comprising movable

members having pivot connections with the rear ends of said lifting member and frame for elevating the latter; said motor pivot connections being so located that the axis of said motor is inclined upwardly and away from the front of the jack, and said load elevating portion having such an extended position adjacent the front wheeling devices, as to provide increased bumper clearance when the jack is collapsed, such dissymmetrical 10 positioning of said pivot devices substantially increasing the stability of the jack when in raised position.

ALEXIS JACKSON.
